UNITED STATES PATENT OFFICE.

THEODORE H. KRUEGER, OF NEW YORK, N. Y.

ENVELOPE.

Application filed January 7, 1921. Serial No. 435,633.

This invention relates to improvements in envelopes and the like and has for its object to provide an envelope provided with means for carrying the envelope in a convenient manner and for maintaining the envelope closed.

More specifically the invention has for its object to provide an envelope having means for carrying the envelope, which means also serve to maintain the envelope closed. Further objects of the invention are to provide an envelope which is simple in construction, economical to manufacture, and which may be quickly and easily closed or opened.

15 In the accompanying drawings forming part of this specification, wherein I have shown several preferred embodiments of my invention for the purpose of illustrating the principle thereof,

20 Figure 1 is an elevational view of a portion of an envelope constructed in accordance with and embodying my invention, the flap being shown closed;

Figure 2 is a view similar to Figure 1, the flap being shown open;

Figure 3 is a sectional view taken on the line III—III of Figure 2;

Figures 4 and 5 are views similar to Figures 1 and 2 showing a modified form of envelope;

Figure 6 is a sectional view taken on the line VI—VI of Figure 4;

Figure 7 is a sectional view taken on the line VII—VII of Figure 5, and

35 Figure 8 is a view similar to Figures 1 and 4 showing a further modification.

Referring to Figures 1, 2 and 3, the envelope is shown as comprising a body portion 1 and a flap 2, it being understood that the envelope may be of any desired shape and size and that it may be made in any suitable manner. Extending upwardly from the rear wall of the body portion 1, and preferably formed integral therewith, is a tongue 3 constituting a carrier portion, the upper end of which projects beyond the envelope and is shaped to form a handle 4 adapted to be grasped by one or more fingers of the hand to permit the envelope to be carried in a convenient manner. The carrier portion 3 and a portion of the rear wall of the envelope is preferably strengthened or reinforced by means of a strip 5 of paper, gummed tape, or other suitable material. The flap 2 of the envelope has a transverse slot 6 formed therein through which the car-

rier portion is adapted to pass when the flap is closed, as indicated in Figure 1, whereby the flap will be maintained in its closed position. To open the envelope it is merely necessary to raise the flap and at the same time withdraw the upper end of the carrier portion from the slot 6.

Referring to Figures 4 to 7, the front wall of the body portion 1 of the envelope is provided with a transverse slot 7 adjacent its edge and the flap 2 is provided with a similar slot 8 adapted to register with the slot 7 when the flap is closed, as shown in Fig. 6. The carrier portion 9, which is similar to the carrier portion 3 shown in Figures 1, 2 and 3, is extended downwardly below the edge of the rear wall of the body portion by forming slits 10 in the rear wall at either side of the carrier portion, the slits being of such length that their lower ends will extend below the flap of the envelope when in its closed position, as clearly shown in Figure 4. When the flap is thus closed, the carrier portion 9 is passed through the registering slots 7 and 8, as shown in Fig. 6, and as the lower end of the carrier portion then overlies the flap, the latter will be held in its closed position. The envelope is carried by grasping the upper end of the carrier portion which projects beyond the envelope and is shaped to form a suitable handle 11. If desired a suitable reinforcing member 12 may be applied to the envelope as explained above in connection with Figs. 1, 2 and 3. To open the envelope it is merely necessary to withdraw the carrier portion from the slots 7 and 8, whereupon the flap 2 may be raised.

The envelope shown in Fig. 8 is similar in construction to that shown in Figs. 4 to 7, but instead of having slots formed in the body portion and the flap, as shown in Figs. 4 to 8, the envelope shown in Fig. 8 has a pair of aligned slots 13 formed in the flap 2 and the carrier portion 14 is threaded through these slots as shown, whereby the flap is held in its closed position.

It will of course be understood that the size and shape of the several carrier portions and of the handles may be varied without departing from the spirit of the invention.

While I have illustrated and described my invention in connection with several preferred embodiments thereof, it will be understood that I do not intend to limit

myself to the specific embodiments shown, but that I intend to cover my invention broadly in whatever form its principle may be employed.

5 Having thus described my invention, I claim:

1. An envelope including a body portion having a slot formed in the front wall thereof, a flap having a slot formed therein adapted to register with the slot in said body portion when said flap is closed, and a carrier portion integral with the rear wall of said body portion adapted to extend through said registering slots to maintain said flap closed.
- 10 2. An envelope having a closure flap and comprising a carrier member of the material of the envelope, said member being shaped to provide a hand-hold portion at its outer end, and said envelope being provided with a pair of narrow slots through which the outer end of said member may be threaded successively to constitute a lock for the closure flap.
- 15 3. A receptacle comprising a body portion,

a flap portion extending from the face wall of the body portion, and an integral carrier member extending from the rear wall of the body portion to a position outside the receptacle when same is closed, said receptacle being provided with a plurality of slots for receiving said carrier portion to hold said flap closed.

4. A receptacle comprising a body portion and an integral reinforced carrier portion, a flap for closing the opening of the receptacle, said body portion and flap being provided with slots adapted to register with each other when the flap is folded over said body portion, and said carrier portion having a width corresponding to the length of said slots and being adapted to be extended therethrough to maintain the flap in closed position and to extend above the top edge of the receptacle when closed to provide a carrier therefor.

In testimony whereof I have affixed my signature to this specification.

THEODORE H. KRUEGER.
